FISHING LURE

Bradford C. Driggers, 3102 Cloverhurst Drive,
East Point, Ga. 30044

Filed Feb. 16, 1967, Ser. No. 5,838

Term of patent 14 years

(Cl. D22—27)

FIG. 1 is a perspective view of a fishing lure showing my new design;

FIG. 2 is a side elevation thereof; and

FIG. 3 is a top plan view thereof.

The dominant features of my design reside in the full line portions shown.

I claim:

The ornamental design for a fishing lure, as shown and described.
